(57) **CLAIM**

The ornamental design for a softstarter, as shown and described.

DESCRIPTION

FIG. 1 is a front view of a softstarter showing our new design;

FIG. 2 is a top perspective view thereof;

FIG. 3 is a bottom perspective view thereof;

FIG. 4 is a right side view thereof,

FIG. 5 is a left side view thereof,

FIG. 6 is a back view thereof.

FIG. 7 is a top view thereof; and,

FIG. 8 is a bottom view thereof.

The broken line showing in the figure drawings is included for illustrative purposes only and forms no part of the claimed design.
